(57) **CLAIM**

The ornamental design for a display box, as shown and described.

DESCRIPTION

FIG. 1 is a front perspective view of a display box, showing our new design;

FIG. 2 is a front elevational view thereof;

FIG. 3 is a left side elevational view thereof; the right side elevational view is the mirrored view thereof; and,

FIG. 4 is a top plan view thereof.

The rear and bottom of the display box are flat and unornamented.

The broken lines in the figures illustrate portions of the article that form no part of the claimed design.

1 Claim, 4 Drawing Sheets
